UNITED STATES PATENT OFFICE.

CHRISTIAN HANSEN, OF SAN ANTONIO, TEXAS, ASSIGNOR OF ONE-HALF TO LAWRENCE N. BREEDING, OF SAN ANTONIO, TEXAS.

LOCK FOR TOY BANKS.

No. 925,900.

Specification of Letters Patent.

Patented June 22, 1909.

Application filed June 13, 1908. Serial No. 438,326.

To all whom it may concern:

Be it known that I, CHRISTIAN HANSEN, a citizen of the United States, and a resident of San Antonio, in the county of Bexar and State of Texas, have invented a new and Improved Lock for Toy Banks, of which the following is a full, clear, and exact description.

My invention relates to toy banks, and has for its object to provide a bank with a door to which is secured a receptacle which is adapted to contain camphor, menthol, or other similar substance, which will gradually decrease in size when exposed to the air, there being a supported bolt on which there is a plate which is adapted to press against the contents of the box; a bar being secured to the door post, a pawl being pivoted to the bolt, a spring being mounted on the bolt, which is adapted not only to press the plate against the contents of the box, but which is also adapted to keep the pawl in engagement with the bar; the bar which is secured to the door post having a free terminal which will permit the pawl to slide off therefrom, to unlock the door; and I also provide an indicator on the front of the door which is adapted to show the position of the pawl relatively to the said bar.

In this specification I will describe the preferred form of my invention, but I do not limit myself thereto, as I consider myself entitled to all forms and embodiments of the invention which may be held to fall within the scope of the appended claims.

Reference is to be had to the accompanying drawings, forming a part of this specification, in which similar characters of reference indicate corresponding parts in all the figures, in which—

Figure 1 is an elevation showing the exterior of a bank door, to which my invention has been applied; Fig. 2 is an interior view of the bank door to which my invention has been applied; Fig. 3 is a sectional view on the line 3—3 of Fig. 2; Fig. 4 is a sectional view on the line 4—4 of Fig. 2; and Fig. 5 is a sectional view on the line 5—5 of Fig. 3.

It will be understood that my invention is particularly designed for use in connection with toy banks, and that the toy bank 1 may

be constructed in any approved manner and that the door 2 may hinge thereto, in any appropriate method which is familiar to those acquainted with the art. To the door 2 is secured a receptacle 3 which is adapted to contain camphor, menthol, or other similar material which will decrease in size when exposed to the air, the receptacle having one side 4, open to permit of a plate 5 having sliding engagement with the interior of the box; the plate 5 being mounted on a hollow bolt 6 which is supported on a stem 7, which is secured to the bank door 2 by means of a flange 8. A pawl 9 is secured to the hollow bolt 6 and is adapted to move therewith when the hollow bolt 6 slides on the stem 7. A coil spring 10 is disposed on the hollow bolt 6, one terminal of the spring being secured to the pawl 9 and the other terminal being secured to the bearing 11 which is secured to the door 2. The coil spring 10 serves two purposes; one of which is to press the hollow bolt 6 with the plate 5, so that the plate will press on the contents of the receptacle 3, and the other purpose is to keep the pawl 9 in engagement with a bar 12, which is secured to a door post 13, by means of a flange 14. To the plate 5 is secured a rod 15 which engages an arm 16 secured to a stud 17, which is journaled in the door 2, and to which, on the outside of the door is secured a pointer 18.

In using my invention, the parts are constructed and are disposed as has been indicated, with a quantity of camphor, menthol or other similar substance 19 disposed in the receptacle 3, or if desired, this receptacle 3 may be so constructed that substances which will diminish in size when exposed to the air, may be introduced as desired by the user of the bank. The substance 19, having been introduced into the receptacle 3, the door of the bank is closed, when the pawl 9 will engage the bar 12 and will be held in this engagement by means of a coil spring 10. The bank will then be found to be locked, and until the substance 19 so decreases in size as to permit the plate 5 to assume with the hollow bolt 6, such a position with reference to the receptacle 3, which will permit the bolt, which is adapted to travel with the hollow bolt, to slip off the

free terminal of the bar 12. When the pawl 9 does slip off the bar 12, the door of the bank will be found to be unlocked.

Having thus described my invention, I 5 claim as new and desire to secure by Letters Patent:

1. In a bank, a receptacle for material which will diminish in size when exposed to the air, means which are adapted to press 10 against the contents of the receptacle, and means which are adapted to secure the door to the door post of the bank, the last named means being adapted to be freed by the first named means.

15 2. In a bank, a receptacle for material which will diminish in size when exposed to the air, means which are adapted to press against the contents of the receptacle, means to so press the first named means, and means 20 which are adapted to secure the door to the door post of the bank, the said means being adapted to be operated by the first named means.

25 3. In a bank, a door therefor, a receptacle for material which will diminish in size when exposed to the air, means which are adapted to lock the door of the bank, the said means being adapted to travel relatively to the receptacle, and means for controlling the position of the said means, the 30 last named means being adapted to press on the contents of the receptacle.

35 4. In a bank, a door therefor, a receptacle for material which will diminish in size when exposed to the air, a bar, means in connection with the bar which are adapted to lock the door, and a bolt to which the 40 said means are secured, the bolt being adapted to travel and to press against the contents of the receptacle.

45 5. In a bank, a door therefor, a receptacle for material which will diminish in size when exposed to the air, a bar, means in connection with the bar which are adapted to lock the door, a bolt to which the said means are secured, the bolt being adapted to travel and to press against the contents of the receptacle, and a spring which is adapted to press the bolt against the 50 contents of the receptacle.

55 6. In a bank, a door therefor, a receptacle for material which will diminish in size when exposed to the air, a bar, means in connection with the bar which are adapted to lock the door, a bolt to which the said means are secured, the bolt being adapted to travel and to press against the contents of the receptacle, and means for pressing the bolt against the contents of the 60 receptacle and for holding the first named means in yielding engagement with the bar.

65 7. In a bank, a door therefor, means on the door, means on the door post, the said means on the door being adapted to engage the means on the door to lock the door,

and a receptacle which is adapted to contain material which will diminish in size when exposed to the air, one of the said means being adapted to press on the contents of the receptacle.

70 8. In a bank, a door therefor, a receptacle for material which will diminish in size when exposed to the air, a bar, a bolt which is adapted to press on the contents of the receptacle, the bolt being adapted to travel relatively to the receptacle, and means in connection with the bolt which are adapted to engage the bar to lock the door.

75 9. In a bank, a door therefor, a receptacle for material which will diminish in size when exposed to the air, one end of the receptacle being open, a bar, a bolt, a plate mounted on the bolt, the plate being adapted to press on the contents of the receptacle, the bolt being adapted to travel relatively to the receptacle, and means in connection with the bolt which are adapted to engage the bar to lock the door.

80 10. In a bank, a door therefor, a receptacle for material which will diminish in size when exposed to the air, a bar, a bolt which is adapted to press on the contents of the receptacle, a support for the bolt with which the bolt has a sliding engagement, and means in connection with the bolt which are 85 adapted to engage the bar to lock the door.

85 11. In a bank, a door therefor, a receptacle for material which will diminish in size when exposed to the air, the receptacle 100 being open at one end, a bar, a bolt, a plate mounted on the bolt, the plate being adapted to press against the contents of the receptacle, a support for the bolt with which the bolt has a sliding engagement, and means 105 in connection with the bolt which are adapted to engage the bar to lock the door.

110 12. In a bank, a door therefor, a receptacle for material which will diminish in size when exposed to the air, a bar, a bolt which is adapted to press on the contents of the receptacle and which is adapted to move relatively thereto, and a pawl mounted on the bolt, the pawl being adapted to engage the bar to lock the door.

115 13. In a bank, a door therefor, a receptacle for material which will diminish in size when exposed to the air, a bar, a bolt which is adapted to press on the contents of the receptacle and which is adapted to move relatively thereto, a pawl mounted on the bolt, the pawl being adapted to engage the bar to lock the door, and means to press the bolt against the contents of the receptacle.

120 14. In a bank, a door therefor, a receptacle for material which will diminish in size when exposed to the air, the receptacle being open at one end, a bar, a bolt, a plate mounted on the bolt, the plate being adapt- 125

ed for pressing against the contents of the receptacle, a support for the bolt with which the bolt has a sliding engagement, a pawl mounted on the bolt, the pawl being adapted 5 to engage the bar to lock the door, and means for pressing the plate against the contents of the receptacle.

15. In a bank, a door therefor, a receptacle for material which will diminish in 10 size when exposed to the air, the receptacle being open at one end, a bar, a bolt, a plate mounted on the bolt, the plate being adapted for pressing against the contents of the receptacle, a support for the bolt with which 15 the bolt has a sliding engagement, a pawl mounted on the bolt, the pawl being adapted to engage the bar to lock the door, and means for pressing the plate against the contents of the receptacle and for holding the 20 pawl in a sliding engagement with the bar.

16. In a bank, a door therefor, a receptacle which is open at one end, the receptacle being adapted to contain material which will diminish in size when exposed to the air, a 25 hollow bolt, a plate secured thereto, the plate being disposed in the receptacle, a stem disposed within the bolt to serve as a support therefor, the bolt with its plate being adapted to move to different positions 30 relatively to the receptacle, a pawl mounted on the bolt, and a bar with a free terminal, the pawl being adapted to engage the bar to lock the door.

17. In a bank, a door therefor, a receptacle which is open at one end, the receptacle being adapted to contain material which will diminish in size when exposed to the air, a hollow bolt, a plate secured thereto, the plate being disposed in the receptacle, 35 a stem disposed within the bolt to serve as a support therefor, the bolt with its plate being adapted to move to different positions relatively to the receptacle, a pawl mounted on the bolt, a bar with a free terminal, the 40 pawl being adapted to engage the bar to lock the door, and means to press the plate against the contents of the receptacle.

18. In a bank, a door therefor, means on the door which are adapted to engage means

on the door post to lock the door thereto, 50 a receptacle which is adapted to contain material which will diminish in size when exposed to the air, one of the said means being adapted to press on the contents of the receptacle, a pointer on the outside of the bank 55 which is adapted to indicate the relative position of the first named means, and means to so operate the pointer.

19. In a bank, a door therefor, means to lock the door, a receptacle, means connected 60 with the first named means which are adapted to press against the contents of the receptacle, the first named means being adapted to be unlocked when the second named means assumes a predetermined position with reference to the receptacle, a pointer on the outside of the bank which is adapted to indicate the relative position of the first named means, and means to so operate the pointer. 65

20. In a bank, a door therefor, a receptacle for material which will diminish in size when exposed to the air, a bar, a bolt which is adapted to press on the contents of the receptacle, means in connection with the bolt which are adapted to engage the bar 70 to lock the door, a pointer on the outside of the bank which is adapted to indicate the relative position of the bolt, and means to so operate the pointer.

21. A bank, a door therefor, a receptacle 80 open at one end, a bolt, a plate secured to the bolt, the plate being disposed in the receptacle, a support for the bolt with which it has a sliding engagement, a pawl pivoted to the bolt, a bar with a free terminal, the 85 pawl being adapted to engage the bar to lock the door, a pointer on the outside of the bank which is adapted to indicate the relative position of the bolt, and means to operate the pointer. 90

In testimony whereof I have signed my name to this specification in the presence of two subscribing witnesses.
